UNITED STATES PATENT OFFICE.

JOHN A. KULLER, OF BROOKLYN, NEW YORK.

LOCK DEVICE.

1,385,558.

Specification of Letters Patent. Patented July 26, 1921.

Application filed July 3, 1920. Serial No. 393,855.

To all whom it may concern:

Be it known that I, JOHN A. KULLER, a citizen of the United States, and residing at Brooklyn, in the county of Kings and State of New York, have invented certain new and useful Improvements in Lock Devices, of which the following is a specification, such as will enable those skilled in the art to which it appertains to make and use the same.

This invention relates to lock devices and particularly to devices of this class designed to be used in connection with doors of various kinds and classes, as for example, the doors of motor vehicles, and the object of this invention is to provide a lock of the class specified, the various parts of which with a few exceptions are composed of sheet metal stampings assembled and secured together in a simple manner. A further object is to provide a lock of the class specified, means whereby the latch bolt may be moved inwardly by door knobs, handles or levers both on the inner and outer side of the door and independent of each other in operation; a further object being to provide means for locking the latch bolt operating means from the outside of the door; a still further object being to provide means for holding the separate latch bolt operating means in neutral position when the latch bolt is automatically moved inwardly and outwardly in the operation of closing the door; and with these and other objects in view the invention consists in a lock device of the class and for the purpose specified which is constructed and operated as hereinafter described and claimed.

The invention is fully disclosed in the following specification, of which the accompanying drawing forms a part, in which the separate parts of my improvement are designated by suitable reference characters in each of the views, and in which:

Figure 1 is a side view of my improved lock device with part of the construction broken away and in section;

Fig. 2 a partial section on the line 2—2 of Fig. 1;

Fig. 3 a partial section on the line 3—3 of Fig. 2;

Fig. 4 a partial section on the line 4—4 of Fig. 2;

Fig. 5 a partial section on the line 5—5 of Fig. 4;

Fig. 6 a partial section on the line 6—6 of Fig. 4; and,

Fig. 7 a partial section on the line 7—7 of Fig. 4.

My improved lock device comprises a suitable casing 10 composed of two sheet metal plates 11 and 12. The plate 11 is oblong and rectangular in form and is provided at one end thereof with an angularly arranged flange 13 the central portion of which is cut out to form an aperture 14 and a portion of the material of said flange is bent upwardly and inwardly to form a guide member 15 for a latch bolt device 16. The plate 12 is fashioned into box-shaped form and the side and end walls of which are provided at intervals with projecting lugs 17 adapted to be passed through apertures 18 in the plate 11 and the protruding portions of said lugs are riveted to secure the separate plates 11 and 12 together. The top of the plate 12 is provided in one end portion thereof with an elongated aperture 19 in which a part of the latch bolt operates.

The plates 11 and 12 are provided approximately centrally thereof with two pairs of apertures 20 and 21 and two roll backs 22 and 23 are mounted within the casing 10 and provided with oppositely directed bearings 24 and 25, which operate respectively in the pairs of apertures 20 and 21, as clearly illustrated in Fig. 2. The roll back 23 is provided with a rectangular aperture 26 adapted to receive a correspondingly formed shank 27 of a knob or handle for the lock device, and which is preferably mounted on the outer side of the door but which is not shown for the reason that it forms no part of this invention. The roll back 23 is provided with a projecting stud 28 which extends through the plate 12 and is provided with a reduced angular shank 29 on which is mounted an operating lever 30 held in place by a screw 31.

The roll back 22 is provided with oppositely extending arms 32 while the roll back 23 is provided with oppositely extending arms 33, as clearly illustrated in Fig. 4 of the drawing. The latch bolt device 16 comprises a latch bolt member 34 which is secured to a latch bolt frame 35, which is composed of an approximately rectangular sheet of metal, one end of which is bent to form a flange 36 provided with a projecting lip 37, which is countersunk in the latch bolt member 34 and secured thereto by welding or otherwise. The frame 35 is also provided with two pairs of projecting members

38 and 39 in connection with which the oppositely directed arms 32 and 33 of the roll backs 22 and 23 operate respectively, as clearly illustrated in Fig. 4.

- 5 Two ears 40 are stamped from the plate 11 at the opposite sides thereof and bent inwardly to form supports for two guide rods 41 which pass through the flange 36 of the latch bolt device 16, or the frame 35 thereof, 10 or upon which said frame is longitudinally movable, and spiral springs 42 are mounted on the rods 41 and normally serve to move the latch bolt device into its operative or projected position.
- 15 Two pairs of spring retaining members 43 and 44 are stamped from the plate 11, one of which is indicated in Fig. 3 of the drawing, and two pairs of spring members 45 and 46 are mounted in the members 43 20 and 44 respectively, and the free ends of said spring members operate in connection with the projecting arms 32 and 33 of the roll backs 22 and 23 respectively and serve to retain said roll backs in their normal position on the inward and outward movement of the latch bolt device in the operation of closing the door.

Mounted in apertures 47 in the plates 11 and 12 is a stub shaft 48, one end of which 30 passes through the plate 11, and is provided with an opening lever 49 held in place by a nut 50, and secured to the shaft 48 within the casing 10 is a pawl 51, the free end portion of which is provided with a V-shaped 35 recess 52 which is adapted to coöperate with one of the arms 33 of the roll back 23, and said pawl is also provided with a shoulder 53 in connection with which one of the projecting members 39 of the latch bolt device 40 16 operates as hereinafter described. A spring 54 is mounted within the casing 10 at one side of the pawl 51 and is held in place by the shaft 49 and by a part 55 on said spring which projects through an aperture 56 in the plate 12. The spring 54 is provided approximately centrally thereof with a projecting catch 57 which is adapted to operate in connection with two elongated grooves or recesses 58 and 59, this construction 45 is clearly illustrated in Figs. 1, 4, 5 and 6 of the drawing. The spring 54 serves to hold the pawl 51 in its operative or inoperative position, said pawl being manipulated through the lever 49 outwardly of the plate 11 and which is located on the inner side of the door.

The operation of my improved lock device will be readily understood from the foregoing description when taken in connection 60 with the accompanying drawing and the following statement. With the pawl 51 in its operative position as illustrated in Figs. 1, 4, 5 and 6 of the drawing, the latch bolt device 16 will not be moved inwardly 65 through the operation of the roll back 22 or

by a handle or knob on the outer side of the door for the reason that the inward movement of the latch bolt device 16, or the frame 35 thereof, is limited by the shoulder 53 on the pawl 51 in connection with which 70 one of the projecting members 39 operates as clearly illustrated in Fig. 1 of the drawing. The latch bolt device 16 may be moved inwardly through the operation of the roll back 23 by the lever 31, it being apparent 75 that in the operation of the roll back 23 the pawl 51 will be raised to move the shoulder 53 out of engagement with the projecting member 39. In this operation of the lock device, the pawl 51 will be locked in its inoperative position by the engagement of the projecting catch 57 on the spring 54 with the recess 59.

The pawl 51 will remain in its inoperative position until the lever 49 is operated to 85 move the same into operative position, and it will be seen from the foregoing that when the pawl 51 is moved into operative position the door cannot be opened from the outer side but may be opened from the inner side, 90 and in which operation the lock pawl 51 is automatically moved into inoperative position. It will be noted that the latch bolt device 16, or the frame 35 thereof, is provided with an elongated aperture 60 through 95 which one of the bearings 24—25 of the roll backs 22 and 23 respectively operate in the inward and outward movement of the latch bolt device.

Having fully described my invention, what I claim as new and desire to secure by Letters Patent, is:

1. A lock device of the class described comprising a casing composed of two sheet metal plates, one of said plates being fashioned into box-shaped form and provided with parts adapted to pass through the other plate and riveted thereto to secure the separate plates together, a tensionally operated latch bolt device mounted between the separate plates of the casing and comprising a bolt proper adapted to normally project through one end wall thereof, a sheet metal guide plate in said casing, two pair of projecting members fashioned from said guide plate, a plurality of roll backs rotatably mounted in the casing and in operative connection with the projecting members of said guide plate, tensional means for holding said roll backs in their normal position, and means coöoperating with said latch bolt device and one of said roll backs for locking the latch bolt device against inward movement by the other of said roll backs.

2. A lock device of the class described comprising a casing composed of two sheet metal plates, one of said plates being fashioned into box-shaped form and provided with parts adapted to pass through the other plate and riveted thereto to secure the sep- 125

- rate plates together, a tensionally operated latch bolt device mounted between the separate plates of the casing and comprising a bolt proper adapted to normally project 5 through one end wall thereof, and a sheet metal guide plate in said casing, two pair of projecting members fashioned from said guide plate, a plurality of roll backs rotatably mounted in the casing and in operative 10 connection with the projecting members of said guide plate, tensional means for holding said roll backs in their normal position, and means coöperating with said latch bolt device and one of said roll backs for locking the latch bolt device against inward movement by the other of said roll backs, whereby 15 the operation of the first named roll back will move said locking device into inoperative position.
- 20 3. A lock device of the class described comprising a suitable box-shaped casing, a latch bolt device mounted in said casing, tensional means adapted to normally project said bolt through one end wall thereof, a 25 plurality of roll backs rotatably mounted in the casing and each of which is adapted to operate said latch bolt device when rotated to the right or to the left, other tensional means for holding said roll backs in their 30 normal position, means coöperating with the latch bolt device and one of said roll backs for locking the latch bolt device against inward movement by the other of said roll backs, and means whereby the operation of 35 the first named roll back will move said locking means into inoperative position.
4. A lock device of the class described comprising a suitable box-shaped casing, a latch bolt device mounted in said casing, 40 tensional means adapted to normally project said bolt through one end wall thereof, a plurality of roll backs rotatably mounted in
- the casing and each of which is adapted to operate said latch bolt device when rotated to the right or to the left, other tensional 45 means for holding said roll backs in their normal position, a member coöperating with said latch bolt device and one of said roll backs for locking the said latch bolt device against inward movement by the other of 50 said roll backs, means for operating said member and means for holding said member in its operative and inoperative positions.
5. A lock device of the class described comprising a casing composed of two sheet 55 metal plates fashioned into the desired form, means for securing said plates together to form said lock casing, a latch bolt device movable inwardly and outwardly through the one end of said casing and comprising a 60 frame having two pairs of projecting members, two roll backs rotatably mounted in the casing and in operative connection with the separate pairs of said projecting members, one of said roll backs being operated 65 by means at one side of the lock casing, the other of said roll backs being operated by means at the other side of the lock casing, tensional devices operating directly upon the separate roll backs for holding the same 70 in their normal position and manually operated means coöperating with one of said roll backs for locking the latch bolt device against movement by the other of said roll backs.

In testimony that I claim the foregoing as my invention I have signed my name in presence of the subscribing witnesses this 2nd day of July 1920.

JOHN A. KULIER.
